UNITED STATES PATENT OFFICE.

EDWARD B. COMERFORD, OF NEW YORK, N. Y.

DESIGN FOR A PUZZLE BOX OR CASE.

SPECIFICATION forming part of Design No. 34,383, dated April 16, 1901.

Application filed March 22, 1901. Serial No. 52,439. Term of patent 3½ years.

To all whom it may concern:

Be it known that I, EDWARD B. COMERFORD, a citizen of the United States, residing at New York, in the county of New York and State of New York, have invented and produced a new and original Design for Puzzle Boxes or Cases, of which the following is a specification, reference being had to the accompanying drawings, forming part thereof, in which—

Figure 1 is a plan view of a puzzle box or case, showing my new design; and Fig. 2, a transverse section thereof on the line 2 2 of Fig. 1.

My newly-designed puzzle box or case is rectangular in form, and the leading or material feature thereof consists of the bottom 5 of said box or case, the center of which is provided with a large five-pointed star 6, which is painted, printed, stamped, or otherwise formed thereon and the separate points of which are of different colors, the said bottom 20 of said box or case being also provided between the points of the star 6 with supple-

mental stars 7, said supplemental stars being 25 each of a different color, the color of said supplemental stars being made to correspond with the color of the separate points of the main central star 6, and said supplemental stars being each also provided at the center 30 with a cavity or recess 8. The puzzle box or case is also provided with a transparent cover 9, and the surface of the bottom thereof is plain and smooth throughout.

Having fully described my invention, what 35 I claim as new, and desire to secure by Letters Patent, is—

The design for a puzzle box or case herein shown and described.

In testimony that I claim the foregoing as 40 my invention I have signed my name, in presence of the subscribing witnesses, this 20th day of March, 1901.

EDWARD B. COMERFORD.
